UNITED STATES PATENT OFFICE

132,760

DESIGN FOR A PLATE OR SIMILAR ARTICLE

William Bruning, New York, N. Y., assignor to Mayer China Company, Beaver Falls, Pa., a corporation of Pennsylvania

Application April 18, 1942, Serial No. 106,681

Term of patent 14 years

To all whom it may concern:

Be it known that I, William Bruning, a citizen of the United States, residing at New York, New York, have invented a new, original, and ornamental Design for a Plate or Similar Article, of which the following is a specification, reference being had to the accompanying drawing, forming part thereof.

The drawing is a top plan view of a plate showing my new design.

The dominant feature of the design is the surface ornamentation appearing on the article,
and while shown applied to a plate, said ornamentation is intended to be applied to other similar articles.

I claim:

The ornamental design for a plate or similar article, substantially as shown and described.

WILLIAM BRUNING.
